UNITED STATES PATENT OFFICE.

WILLIAM J. OMER, OF THOMAS, OKLAHOMA.

CARBURETER.

1,105,371.

Specification of Letters Patent. Patented July 28, 1914.

Application filed May 29, 1914. Serial No. 841,820.

To all whom it may concern:

Be it known that I, WILLIAM J. OMER, a citizen of the United States, and a resident of Thomas, in the county of Custer and State of Oklahoma, have invented a new and useful Improvement in Carbureters, of which the following is a specification.

My invention is an improvement in carbureters, and has for its object to provide a device of the character specified, adapted for use with internal combustion engines of every character, wherein mechanism is provided for thoroughly volatilizing gasoline or other liquid fuel, and for mixing the volatilized fuel with air to provide for perfect combustion of the fuel.

The primary object of the invention is to provide mechanism for controlling the mixture without the use of the usual float valves, and without the necessity for adjusting the relative proportions of fuel and air in accordance with conditions of load and road.

A further object is to provide mechanism in connection with the carbureter for heating the mixture, before it passes to the combustion chamber of the engine.

In the drawings:—Figure 1 is an enlarged section taken on the line 1—1 of Fig. 3, Fig. 2 is a section on the line 2—2 of Fig. 1, Fig. 3 is a top plan view with parts broken away, and Fig. 4 is a partial side view of a modified construction.

The present embodiment of the invention is shown in connection with the fuel tank 1, of an internal combustion engine, the tank being of any usual or desired form, and of any desired capacity and being a closed receptacle as shown. A tubular casing or pipe 2 is arranged at the center of the tank, extending through the top or cover thereof to a point near the bottom of the tank. At its upper end the pipe 2 is integrally connected to the cover by means of a ring 3, which extends above and below the top.

Above the top the ring is reduced annularly to form a shoulder 4 near the upper end thereof and above the shoulder the ring is screw threaded to receive a cover. The cover comprises a concavo-convex top 5 arranged with its convex surface upward, and an internally threaded ring 6 which engages the threaded portion at the top of the pipe 2, and the top 5 is connected to the ring by arms 7, the said arms being arranged at

angular intervals of 90° with respect to each other. The cover is square as shown in Fig. 3, and the arms 7 are at the corners. The arrangement of the arms 7 provides for four openings for placing the interior of the cover in communication with the atmosphere. The openings are normally closed by means of gates or valves 8, of frusto-pyramidal form, each valve or gate being hinged to the cover as indicated at 9, at the outer edge of the gate or valve. The pipe 2 is provided with a number of annular series of openings 11 near its upper end, and commencing just below the ring. A tubular structure is arranged within the tank at the top thereof, the said structure consisting of a series of straight sections 12, and elbows 13 and 14 for connecting the ends of the straight sections with each other. The elbows 13 and 14 are merely tubular, but the sections 12 may be described as split tubes and they are arranged with the split on the under side thereof. Each of the said sections is provided at each side of the split with a depending flange 15, and the flanges 15 of each section are arranged in spaced and parallel relation. A sheet of wicking is supported by each of the sections 12 of the tubular structure, the said sheet being doubled upon itself to form folds 16 and 16^a. The junction between the folds of each sheet is held within the adjacent section 12, and mechanism is arranged within the fold for holding the said fold or junction in close contact with the interior of the section. This mechanism in the present instance, is a tubular casing 17 of gauze or the like, of such cross section that it will fit within the wicking when the wicking is in contact with the interior of the section. The folds 16 and 16^a depend through the split of the section, and between the flanges 15 of the section to a point at or near the bottom of the tank.

The sections 12 are held in position near the top of the tank and above the level of the liquid therein by means of transverse partitions 19, and each of the said partitions 19 is provided with an opening 20 at its bottom for placing the entire tank in communication. The lower edges of the flanges 15 are bent outwardly as shown at 21, and the said lower edges rest upon the upper edges of the partitions 19.

Deflecting plates 22, 23 and 24 are arranged between the flanges 15 of the adja-

cent section 12, the said plates differing only in width. The plates 22 are arranged between the side walls of the tank and the adjacent flange 15 of the adjacent section 12. 5 The plate 24 is arranged at the center of the tank between the two central sections, and the plates 23 are arranged between the lateral section at each side of the tube 2. Each of the plates 22, 23 and 24 is bent at its center to form two portions extending at an obtuse angle with respect to each other, and the free edge of each plate is flanged downwardly as indicated at 25, and fitted against the adjacent flange 15 and the side wall of 10 the casing and is secured to the flange or to the casing by rivets 26. At the flanges 15 the rivets 26 pass through the flanges and the adjacent folds of the wicking, and the flanges 15 are further connected by other 15 rivets 27, arranged below the rivets 26. Each of the plates 22, 23 and 24 is provided with a longitudinal series of openings 28 at its center, and the plate 24 has an opening through which the pipe 2 passes. The folds 20 of wicking extend only to the ends of the sections 12, but the plates 22, 23 and 24 extend from one end of the casing to the other, and are continued along the ends of the casing as indicated at 29. The plates 22—23— 25 30 24 and 29 are in fact an integral structure which divide the tank into upper and lower compartments, the liquid fuel being below the said partition, and the openings 28 provide a communication between the compartments. 35

It will be noted from an inspection of Figs. 1 and 3 that the outermost section 12 is extended at one end through the adjacent end of the tank, as indicated at 30, and that 40 the outermost section at the opposite end of the tank extends only about half the length of the tank. An elbow 31 connects the free end of the section with a vertical pipe 32, which passes downwardly from the 45 elbow through the bottom of the tank, being reinforced at the bottom with a ring 33. An elbow 34 is connected with the lower end of the pipe 32 below the ring, and a section 35 of pipe is connected with the other end 50 of the elbow. The pipe 35 is adapted for connection with the manifold of the engine, either directly or indirectly as conditions may require. The usual throttle valve 36 is arranged in the section 35 of pipe, the valve being secured to the shaft or rod 37, journaled 55 transversely of the pipe and provided at its outer end with the arm 38 for manipulating the shaft. Screens 39 and 40 are arranged within the pipe 25 at spaced intervals, for 60 preventing damage from back firing. Should the flame from back firing pass the throttle valve, it would be checked by the screen.

A valve 41 is arranged within the extension 30, the said valve co-operating with the 65 seat 42, and the valve is provided with a

stem 43, passing through a spider 44 in the pipe for guiding the stem. A coil spring 45 encircles the stem between the spider and a stop 46 threaded on to the rod, the spring acting normally to hold the valve closed. The stop in the present instance is a nut and washer, and it will be evident that the tension of the spring may be varied by moving the nut. One end of the spring is connected to the spider and the other to the stop. In case of back firing the valve will relieve any excess pressure in the tubular structure, and the valve may also be used for admitting air when necessary. The spring 45 may be arranged to hold the valve partially open in order to admit air when conditions require more air than enters by way of the valves 8 and the openings 41 of the pipe 2.

The device is also arranged in such manner that it may be utilized as a self starter for the engine. For this purpose a nipple or tube 47 is arranged transversely of the top and extending through the same, and the outer end of the tube is adapted for connection with a flexible pipe 48, the other end of which is connected with a suitable compressing device, as for instance, any means for compressing air, such as a bulb or pump. When it is desired to start the engine in this manner air under pressure is forced through the tube 47, and this air under pressure will enter the openings 18, and will pass through the tubular structure and the pipes 32 and 35 to the engine.

Mechanism may also be arranged within the tank 1 for heating the tubular structure, consisting of the pipes 12 and the elbows 13 and 14. This mechanism is shown in Fig. 4, wherein resistance wires 49 and 50 are arranged on opposite sides of the openings 18^a in the sections 12^a of the tubular structure. These sections have the depending flanges 15^a, corresponding to the flanges 15, and the folds 51 of wicking are connected therewith and with the sections in the same manner as above described. The resistance wires 49 and 50 are connected with a suitable source of electrical energy capable of heating the wires. It will be obvious that when so connected the pipes will be heated and the mixture passing through the pipes will be heated during its passage through the pipes. It will be understood that any form of heater may be used in this connection.

The operation of the improved carburetor 120 is as follows:—The fuel tank is filled with liquid fuel to about the level shown, and in a very short time the depending folds 16 and 16^a will become saturated with the fuel and by capillary attraction the fuel will pass 125 into the tubular casing. The wick acts in the same manner as the wick of an oil lamp and it will be evident that so long as there is any fuel in the tank it will be drawn into the tube. After the wicking has been thor- 130

oughly saturated in this manner, whenever the engine is started in the usual manner air will be drawn through the openings in the cover 5, lifting the valves 8 and passing into the tube 2 and entering the body of the tank through the openings 11. From the interior of the tank the air will be drawn into the tubular structure through the openings 18, and will vaporize the fuel held by the wicking. As the air passes through the openings 18 and through the wicking to the interior of the tubular structure it will vaporize the fuel held by the wicking and will carry the same through the tubular structure to the engine. When the heating device is used in connection with the tubing the air will be heated as it passes to the engine. In case a mixture of less richness were required the valve 41 would be open to admit a greater quantity of air. When it is desired to fill the tank or to renew the fuel the cover 5 is turned off from the upper end of the pipe 2, and the fuel is poured through the pipe 2 into the tank. The plates 22—23—24 are baffle plates to prevent the fuel splashing into the upper part of the tank, and to prevent any non-volatilized fuel passing through the engine. Any fuel that would pass above the plates will be returned to the body of the tank through the openings 28.

I claim:

1. A device of the character specified, comprising a closed tank having a central filling tube extending through the top thereof, and below the normal level of the liquid fuel, and having openings above the normal level, a removable cover for the tube, said cover having openings, gates or valves normally resting over the openings and closing the same and adapted to open to admit air to the tube, and a tubular structure supported within the tank near the top thereof and above the fuel, said structure comprising straight sections and elbows for connecting the straight sections, the straight sections being split and having the split at the under side and having flanges at the sides of the split depending in approximate parallelism, a sheet of wicking connected with each of the said straight sections, each sheet being doubled upon itself and having the junction within the tube and having the folds extending through the split to near the bottom of the tank, said split tubes having openings for admitting air to the tube through the wicking, the ends of the tubular structure being extended outside the tank, the entrance end having a spring actuated valve for normally closing the same, and screens arranged transversely of the exit end, and depressions and openings at the bottoms of the

2. A device of the character specified, comprising a closed tank having a central filling tube extending through the top thereof and below the normal level of the liquid fuel, and having openings above the normal level, a removable cover for the tube, said cover having openings, gates or valves normally resting over the openings and closing the same and adapted to open to admit air to the tube, and a tubular structure supported within the tank near the top thereof and above the fuel, said structure comprising straight sections and elbows for connecting the straight sections, the straight sections being split and having the split at the under side, and having flanges at the sides of the split depending in approximate parallelism, a sheet of wicking connected with each of the said straight sections, each sheet being doubled upon itself and having the junction within the tube and having the folds extending through the split to near the bottom of the tank, said split tubes having openings for admitting air to the tube through the wicking, the ends of the tubular structure being extended outside the tank, the entrance end having a spring actuated valve for normally closing the same, and screens arranged transversely of the exit end.

3. A device of the character specified, comprising a closed tank having a central filling tube extending through the top thereof and below the normal level of the liquid fuel and having openings above the normal level, a removable cover for the tube, said cover having openings, gates or valves normally resting over the openings and closing the same and adapted to open to admit air to the tube, and a tubular structure supported within the tank near the top thereof and above the fuel, said structure comprising straight sections and elbows for connecting the straight sections, the straight sections being split and having the split at the under side, a sheet of wicking connected with each of the said straight sections, each sheet being doubled upon itself and having the junction within the tube and having the folds extending through the split to near the bottom of the tank, said split tubes having openings for admitting air to the tubes through the wicking, the ends of the tubular structure being extended outside the tank, the entrance end having a spring actuated valve for normally closing the same, and screens arranged transversely of the exit end.

4. A device of the character specified, comprising a closed tank having a central filling tube extending through the top thereof and below the normal level of the liquid fuel and having openings above the normal level, a removable cover for the tube, said cover having openings, gates or valves normally resting over the openings and closing

- the same and adapted to open to admit air to the tube, and a tubular structure supported within the tank near the top thereof and above the fuel, said structure comprising 5 straight sections and elbows for connecting the straight sections, the straight sections being split and having the split at the under side, a sheet of wicking connected with each of the said straight sections, each sheet being 10 doubled upon itself and having the junction within the tube and having the folds extending through the split to near the bottom of the tank, said split tube having openings for admitting air to the tube through 15 the wicking, the ends of the tubular structure passing outside of the tank, one end being adapted for connection with the engine, and a spring actuated valve normally closing the other end.
- 20 5. A device of the character specified, comprising a closed tank having a filling tube extending through the top thereof and below the normal level of the fuel, said tube having openings above the level of the fuel, a cover 25 for the tube provided with inlet openings, and a tubular structure supported within the tank near the top thereof and above the normal level of the fuel, said structure having sections of split tubing arranged with the 30 split below, and wicking within the split tubes and extending through the split to near the bottom of the tank, said sections having openings, one end of the tubular structure being adapted for connection with the 35 engine, and the other end having a spring actuated normally closed valve, and means for heating the tubular structure.
- 40 6. A device of the character specified, comprising a closed tank having a filling tube extending through the top thereof and below the normal level of the fuel, said tube having openings above the level of the fuel, a cover 45 for the tube provided with inlet openings, and a tubular structure supported within the tank near the top thereof and above the normal level of the fuel, said structure having sections of split tubing arranged with the split below, and wicking within the split tubes and extending through the split to

near the bottom of the tank, said sections 50 having openings, one end of the tubular structure being adapted for connection with the engine, and the other end having a spring actuated normally closed valve.

7. A device of the character specified, comprising a closed tank having a filling tube extending through the top thereof and provided with openings in the tank above the normal level of the fuel, a removable cover for the tube having inlet openings, and a 60 tubular structure supported within the tank near the top thereof and above the normal level of the fuel, said structure being adapted for connection to the engine at one end, said structure having sections of split tubing 65 arranged with the split below, and a sheet of wicking connected with each section each sheet being doubled upon itself and having the junction within the tube and the folds extending through the split to near the 70 bottom of the tank, a perforate framework within the tube, and of approximately cylindrical form and holding the wicking against the inner face of the tube, each section having openings near the split for admitting air 75 through the wicking.

8. A device of the character specified, comprising a closed tank having a filling tube extending through the top thereof and provided with openings in the tank above the 80 normal level of the fuel, a removable cover for the tube having inlet openings, and a tubular structure supported within the tank near the top thereof and above the normal level of the fuel, said structure being adapted for connection to the engine at one end, said structure having sections of split tubing 85 arranged with the split below, and a lining of wicking for each section and depending through the split to near the bottom of the 90 tank, each section having openings for permitting the entrance of air through the wicking, one end of the said tubing being adapted to be connected with the engine.
